UNITED STATES PATENT OFFICE

2,333,974

RAILWAY TRAFFIC CONTROLLING APPARATUS

Charles W. Bell, Forest Hills, Pa., assignor to The Union Switch & Signal Company, Swissvale, Pa., a corporation of Pennsylvania.

Application June 7, 1941, Serial No. 397,097.

4 Claims. (Cl. 246—26)

My invention relates to railway traffic controlling apparatus, and more particularly to apparatus for use in connection with remote control systems for railways.

Remote control systems for railways are used for governing widely spaced track switches and signals from a central office station, such control being effected by the sending of control influences or codes from the office station to field stations located one at each track switch and signal location. These control influences or codes are distinctive for each such field station and are further made distinctive for the different switches and signals associated with each field station. Indication influences or codes are sent from each field station to the office station in order to keep the operator informed as to the condition of the various switches and signals and as to the presence of trains in the vicinity of a field station. Electric locking between the several manually controlled elements or levers at the office station by which the codes are initiated is desirable to assure that signals for conflicting track routes are not inadvertently cleared by the operator.

Accordingly, a feature of my invention is the provision of railway traffic controlling apparatus incorporating novel means for electric locking in remote control systems for railways. Another feature of my invention is the provision of apparatus of the above character wherewith the sending of a control influence for clearing a signal is prevented when an opposing signal has been cleared. Again, a feature of my invention is the provision of reverse signaling apparatus incorporating novel means for indicating occupancy of the stretch between the associated signals and the direction the train is moving through the stretch. Still another feature of my invention is the provision of novel means for control of a traffic locking circuit used in connection with a remote control system for railways. Other objects, purposes and features of my invention will become apparent from the following description.

In carrying out the above features, objects and advantages of my invention, I use the usual directional stick or traffic following relay of a traffic locking circuit to effect through the medium of the code equipment of a remote control system associated with the stretch of railway electric locking in the office station code sending apparatus, and which electric locking once a signal is cleared is maintained against the clearing of an opposing signal while the train travels the entire stretch to the opposing signal. This same directional stick relay is also used through the

medium of the code equipment of the associated remote control system, to control an office station directional indicator which indicates the direction in which the train is moving through the stretch. As an alternative arrangement such directional stick relay is used to control through the code equipment a single non-directional indicator to indicate occupancy of the stretch. Furthermore, I preferably use the usual directional repeater or lockout relay of the traffic locking circuit to maintain a field station lockout for the opposing signal until the office station electric locking has had time to become effective.

Use of the relays of a traffic locking circuit in the manner here contemplated obtains the advantages of electric locking for opposing signals of a stretch of track over which trains may move in either direction without use of special line circuits to repeat the various track circuits of the stretch. Also, directional and non-directional track occupancy indications are obtained without the use of additional circuits through the stretch.

I shall describe one form of apparatus embodying my invention, and shall then point out the novel features thereof in claims.

The accompanying drawing is a diagrammatic view showing one form of apparatus embodying my invention when used with a traffic locking circuit for a stretch of railway having associated therewith a remote control system.

Referring to the drawing, the diagram at the top of the drawing illustrates a stretch of single track railway extending between two locations D and E. As here shown, locations D and E are the adjacent track switch locations of adjacent passing sidings, track switch 1 at location D leading to a passing siding S1 and track switch 3 at location E leading to a passing siding S3. This stretch of track between locations D and E is preferably arranged by means of the usual insulated rail joints into track sections 1T, AT, BT and 3T, sections 1T and 3T being detector sections at switches 1 and 3, respectively, and sections AT and BT being intermediate sections. It is to be understood, of course, that my invention is not limited to this specific arrangement of a stretch of railway or to this specific arrangement of track sections and the stretch may be between two locations other than siding locations and the stretch may be arranged with more or fewer track sections if desired. Each track section is provided with the customary track circuit including a track relay, such track relay being identified by the reference character R plus a

prefix corresponding to the section, and the association of a track relay with its track section being indicated by a dash line.

Before proceeding further with the description, it should be pointed out that contact fingers of these track relays, as well as contact fingers of other relays to be later described, are in some instances shown remote from the winding of the relay. In each such instance, the contact finger is identified by the reference character of the respective relay and by being shown in a position corresponding to the normal position of the relay. Also, it is to be understood that track switches 1 and 3 would have connected thereto switch circuit controllers for opening and closing contacts according to the position of the switch and in order to simplify the drawing, the contacts of such circuit controllers only are shown, the contacts being given as a reference character, the numeral corresponding to that of the associated switch plus the letter N or R according to whether the contact is closed at the normal or reverse position of the switch. Track switches 1 and 3 may be hand or power operated as desired. Preferably, power operation of the switches is provided by the usual standard power switch machines governed by a remote control system to be later described. However, such switch operating apparatus for switches 1 and 3 is not shown in the drawing, since it forms no part of my invention, and is not required for a full understanding of the invention.

At location D, eastbound movements, that is, movements from left to right as viewed in the drawing, are governed by signals R2 and RC2, and opposing westbound movements are governed by signal L2. At location E westbound movements, that is, movements from right to left as viewed in the drawing, are governed by signals L4 and LC4, and opposing eastbound movements are governed by signal R4. Signals R2, L2, R4 and L4 are in each case provided with two signal mechanisms mounted on a single mast, the top and bottom signal mechanism being identified by the reference characters A and B, respectively, plus a prefix corresponding to the signal. It is to be understood that approach signals, not shown, for the signals at locations D and E would be provided in accordance with standard practice.

The type of signal is immaterial and any standard form may be used. The operating circuits for each of these signals are preferably governed by a signal control relay, such relay being identified by the reference character H plus a prefix corresponding to the signal. The operating circuits for signals RA2 and RC2 at location D and signals LA4 and LC4 at location E are the only ones shown in the drawing since these are sufficient for a full understanding of my invention. For example, as shown at the upper left-hand portion of the drawing, an operating circuit for signal RA2 is controlled over front contact 11 of a signal control relay RA2H, the arrangement being that when relay RA2H is picked up closing front contact 11, signal RA2 is operated to a proceed position and when relay RA2H is released opening front contact 11 signal RA2 is operated as required to display a stop indication. The signal control relays of the several signals would be in each case governed by traffic conditions in advance of the signal in accordance with standard practice, and the relays for signals RA2, RC2, LA4 and LC4 are also governed by a

traffic locking circuit with which the apparatus embodying my invention is associated.

Eastbound signals RA2 and RC2 at location D are associated with westbound signals LA4 and LC4 at location E by a traffic locking circuit to provide reverse signaling between the two locations D and E. In the present embodiment of the invention such traffic locking circuit includes a directional relay and a directional repeater or lockout relay as well as a current source at each of the two locations, and such circuit is completed between the two locations over line wires in which there are interposed front contacts of the track relays of the several track sections of the stretch. This traffic locking circuit is further controlled by a manually controlled relay at each of the two locations as will appear hereinafter. It is sufficient at this point of the specification to explain that when an eastbound train movement is to be made from location D, the traffic locking circuit is conditioned by the manually controlled relays for energization of a directional relay R2FR at location D by current supplied to the circuit from a battery 12 at location E, the winding of a lockout relay L4BLR at location E being also interposed in the circuit so that both relays R2FR and L4BLR are normally energized and picked up providing the stretch of track is unoccupied. When a westbound movement is to be made from location E, the manually controlled relays condition the traffic locking circuit for energization of a directional relay L4FR at location E by current supplied to the circuit from a battery 13 at location D, the winding of a lockout relay R2BLR at location D being interposed in the circuit so that both relays L4FR and R2BLR are energized and picked up if the stretch is unoccupied.

Directional relay R2FR when picked up to close front contact 30 completes obvious circuits for signal control relays RA2H and RC2H, a contact 1N closed at the normal position of switch 1 being interposed in the circuit for relay RA2H and a contact 1R closed at the reverse position of switch 1 being interposed in the circuit for relay RC2H. Similarly, directional relay L4FR when picked up closing front contact 31 completes obvious circuits for signal control relays LA4H and LC4H, a contact 3N closed at the normal position of switch 3 being interposed in the circuit for relay LA4H and a contact 3R closed at the reverse position of switch 3 being interposed in the circuit for relay LC4H. Consequently, when eastbound directional relay R2FR is picked up due to the traffic locking circuit being conditioned for eastbound traffic, eastbound signal RA2 or RC2 is cleared depending upon the position of switch 1, and when westbound directional relay L4FR is picked up due to the traffic locking circuit being conditioned for westbound traffic, westbound signal LA4 or LC4 is cleared depending upon the position of switch 3.

Directional stick relays or traffic following relays R2SR and L4SR placed at locations D and E, respectively, are associated with this traffic locking circuit to effect following train movements and in accordance with my invention these relays are used to effect electric locking and track occupancy indication for a remote control system associated with the stretch in a manner shortly to be explained. Looking at relay R2SR, this relay is provided with a pick-up circuit which includes terminal B of any convenient source of current at location D, such as a battery not shown, back contact 15 of track relay 1TR of de-

ector track section 1T, front contact 14 of directional relay R2FR, winding of relay R2SR and terminal C of the same source of current. Relay R2SR is also provided with a stick circuit extending from terminal B of the source of current over back contact 16 of directional relay R2FR, front contact 17 and winding of relay R2SR and to terminal C. In a similar manner, directional stick relay L4SR is provided with a pick-up circuit including terminal B of a convenient source of current at location E, back contact 18 of track relay 3TR for detector track section 3T, front contact 19 of directional relay L4FR, winding of relay L4SR and terminal C; and with a stick circuit including terminal B, back contact 20 of relay L4FR, front contact 21 and winding of relay L4SR and terminal C. It is to be seen, therefore, that when directional relay R2FR has been picked up by the traffic locking circuit being conditioned for eastbound traffic and an eastbound train enters section 1T shunting track relay 1TR, directional stick relay R2SR is picked up over its pick-up circuit during the slow release period of relay R2FR and is then retained picked up due to its stick circuit until such time as the eastbound train vacates the stretch at location E or else backs out of the stretch at location D so that directional relay R2FR is reenergized, it being recalled that contacts of each of the several track relays are interposed in the traffic locking circuit. Also, when directional relay L4FR has been energized by the traffic locking circuit being conditioned for westbound traffic and a westbound train enters section 3T shunting track relay 3TR, directional stick relay L4SR is picked up over its pick-up circuit during the slow release period of relay L4FR and is then retained energized over its stick circuit until such time as this westbound train vacates the stretch at location D or else backs out of the stretch at location E so that directional relay L4FR is reenergized. The manner wherewith directional stick relays R2SR and L4SR function to provide permissive movements as well as being used according to my invention to effect electric locking and track occupancy indications for the associated remote control system will appear hereinafter.

Manual control of this traffic locking circuit and hence of the signals governing traffic between locations D and E is effected by an associated remote control system. Such remote control system may be any one of several well known forms and I shall assume that the remote control system to be used is of the time code type covered by Letters Patent of the United States No. 2,183,155, granted December 12, 1939 to Clarence S. Snavely, et al. for Remote control systems, and to which patent reference is made for a full understanding of such remote control system. It is necessary therefore, to describe such remote control system in the present application only to the extent required for a full understanding of my invention. The remote control system includes a closed line circuit LC which extends between field stations FD and FE at locations D and E, respectively, and a remote office station OF, the circuit being looped through each such station to include the winding of a line receiving relay R and a contact of a transmitting relay T. The circuit LC is supplied with current from a battery 22 placed at the office station OF and is normally energized so that all the line relays R are picked up. When any transmitting relay T is operated to open and close its contact interposed in the circuit in accordance to a prese-

lected time code, the line relays R are operated in unison in accordance with such code.

The apparatus at each station of the remote control system, includes a group of inter-related 5 relays which are referred to as a coding unit and the relays of each such coding unit are arranged to function in a manner either so as to form and send a code or so as to receive and decode a code. Each such coding unit in sending a code causes 10 operation of the associated transmitting relay T according to the preselected code and thus impresses that code upon the line circuit, and each coding unit is responsive to the operation of its 15 respective line relay R to receive and decode any code that is impressed upon the line circuit. At the office station manually operable levers are provided for initiating the sending of a control code by the office station coding unit and at each field station automatic means responsive to the 20 positions of the associated signaling devices is provided for initiating the sending of an indication code by the respective coding unit. By proper manipulation of the levers at the office station an operator can send control codes to the different field stations as desired. Such 25 control codes are received by each field station and the coding unit at the field station for which the code is intended functions to put into effect the control desired by causing a corresponding signal or switch controlling relay to be energized or de-energized as the case may be. Conversely, control of a field station coding unit according to the different positions of the associated signaling devices causes preselected indication codes to 30 be sent from that field station. All indication codes are decoded by the office station coding unit to energize or deenergize, as the case may be, indication relays which cause in turn corresponding indicators to display an indication to inform the operator as to the position of the respective signaling device. The system includes, of course, means to avoid overlapping of such control and indication codes. In the drawing the 35 coding units for stations OF, FD and FE are shown conventionally at CO, CD and CE, respectively, since the specific arrangements of the relays included in such coding units form no part of my invention and are fully described in the aforementioned Patent No. 2,183,155. To aid in the 40 understanding of the present invention, however, two code sending relays CS2 and CS4 of the coding unit CO at the office station and stepping relay 1F2 of the coding unit CD at station FD and stepping relay 3F2 of coding unit CE at station FE are shown in the drawing. Consequently, a control code sent from office station OF to field station FE for control of the 45 traffic locking circuit and in turn for control of signals LA4 and LC4, is received and the code decoded by coding unit CE of station FE, and a control code sent from the office station to field station FD for control of the traffic locking circuit and in turn control of signals RA2 and RC2 is received and decoded by the coding unit CD at station FD.

Coding unit CE puts such control codes into effect through its associated stepping relay 3F2 which controls circuits for a signal controlling relay L4HSR. Relay L4HSR is a two winding polar relay, energized over a first circuit including terminal B of the current source, front contact 32 of relay 3F2, left-hand winding of relay L4HSR as viewed in the drawing, back contact 34 of lockout relay L4BLR and terminal C. Energization of the left-hand winding of relay

L4HSR causes the relay to be energized at normal polarity to operate its polar armature 4 to the normal or left-hand position as viewed in the drawing, that is, to the position opposite that shown in the drawing. Relay L4HSR is also provided with a second circuit which extends from terminal B over back contact 85 of track relay 3TR, front contact 86 of a repeater relay 3TP to be referred to later, back contact 33 of stepping relay 3F2 and right-hand winding of relay L4HSR to terminal C, and relay L4HSR is energized at reverse polarity to operate its polar armature 4 to the reverse or right-hand position as viewed in the drawing. The manner whereby the signal controlling relay L4HSR functions to control the traffic locking circuit will be explained when the operation of the apparatus is described. Again, when a control code is sent to station FD to control the traffic circuit such control code is decoded by coding unit CD to control through stepping relay 1F2 an associated signal controlling relay R2HSR which relay is also a two winding polar relay. Relay R2HSR is provided with a first energizing circuit which is completed from terminal B over front contact 35 of stepping relay 1F2 in the coding unit CD, right-hand winding of relay R2HSR, back contact 37 of lockout relay R2BLR and terminal C, and relay R2HSR is energized at reverse polarity to operate its polar armature 5 to the reverse or right-hand position, that is, to the position opposite that shown in the drawing. Relay R2HSR is energized by a second circuit which extends from terminal B over back contact 87 of track relay 1TR, front contact 88 of a track repeater relay 1TP, back contact 36 of stepping relay 1F2, left-hand winding of relay R2HSR and terminal C, and relay R2HSR is energized at normal polarity to operate its polar armature 5 to the normal or left-hand position. The manner whereby signal controlling relay R2HSR functions to control the traffic locking circuit will also be taken up when the operation of the apparatus is described. Each signal controlling relay R2HSR and L4HSR is preferably of the type that the polar armature remains in its last position when the respective relay is deenergized.

Two indication relays R2BK and L4BK at the office station OF are controlled by directional stick relays R2SR and L4SR, respectively, through the remote control system, relays R2BK and L4BK being each preferably a two winding polar relay whose armature remains in its last position when the relay is deenergized. When directional stick relay R2SR at location D is released to close back contact 38, positive energy is applied to a terminal 41 of the apparatus of field station FD and when relay R2SR is picked up to close front contact 40 positive energy is applied to a terminal 39 of the field station apparatus. Energy on terminals 39 and 40 causes the coding unit CD to send respective indication codes which are decoded by the office station coding unit CO to control polar indication relay R2BK. The arrangement is such that the indication code sent due to the closing of front contact 40 of relay R2SR causes indication relay R2BK at the office station to be energized at normal polarity to close its normal or left-hand polar contacts, and the code sent due to the closing of back contact 38 of relay R2SR causes indication relay R2BK to be energized at reverse polarity to close its reverse or right-hand polar contacts. At location E, the closing of back contact 42 of directional stick relay L4SR applies

positive energy to terminal 43 of the apparatus of field station FE and the closing of front contact 44 of relay L4SR applies positive energy to terminal 45 of the field station apparatus. Energy applied to terminals 43 and 45 initiates the sending of respective indication codes from field station FE which are decoded by the office station coding unit CO to control polar indication relay L4BK, the arrangement being such that the indication code, due to the closing of back contact 42 of relay L4SR causes indication relay L4BK to be energized at reverse polarity to close its reverse or right-hand polar contacts, and the indication code transmitted due to the closing of front contact 44 of relay L4SR causes indication relay L4BK to be energized at normal polarity closing its normal or left-hand polar contact. The functions of indication relays R2BK and L4BK will shortly appear.

The aforementioned Patent No. 2,183,155 explains specifically in connection with Fig. 6 of the patent, that the office station is provided with a code sending or code delivering relay CS for each field station coding unit of the system, each such code sending relay CS being required to be energized and picked up before a control code can be delivered to the line circuit LC for the corresponding field station coding unit. In the drawing, code sending relays CS2 and CS4 of the office station coding unit CO govern the sending of control codes to coding units CD and CE of field stations FD and FE, respectively. In other words, code sending relay CS2 must be picked up in order for a control code to be sent to coding unit CD of station FD to govern signal controlling relay R2HSR and code sending relay CS4 must be picked up in order for a control code to be sent to coding unit CE of station FE to govern the signal controlling relay L4HSR. Each such code sending relay is controlled over a circuit network of the office station coding unit as fully disclosed in Fig. 6 of the aforementioned Patent No. 2,183,155, and which network includes in each case contacts of the various relays for conflicting signals and switches with the result electric locking is obtained between levers for opposing signals and switches governed by the remote control system. In the drawing the coding unit circuit networks for code sending relays CS2 and CS4 are shown conventionally by contacts 23 and 24, respectively, for the sake of simplicity because these networks are not a part of my invention except as they are associated with contacts of the indication relays R2BK and L4BK. That is to say, according to my invention, a reverse polar contact 26 of relay R2BK is interposed in the control network for code sending relay CS4, and a reverse polar contact 25 of relay L4BK is interposed in the control network for code sending relay CS2. It follows that indication relay R2BK governed by indication codes sent by field station FD must occupy its reverse position before a control code can be sent from the office station to the field station FE. Likewise, indication relay L4BK governed by indication codes sent by field station FE must occupy its reverse position before a control code can be delivered to the field station FD.

Indication relays R2BK and L4BK also control directional indicator lamps 46 and 47, respectively, indication lamp 46 being illuminated over an obvious circuit including normal polar contact 48 of relay R2BK, and lamp 47 being illuminated over an obvious circuit including normal polar contact 49 of relay L4BK. As will ap-

pear when the operation of the apparatus is described, lamp 46 when illuminated indicates occupancy of the stretch between locations D and E by an eastbound train and illumination of lamp 47 indicates occupancy of the stretch by a westbound train, an arrow pointing in the direction in which the train is moving in the stretch being preferably placed adjacent each lamp 46 and 47. As an alternative to directional indicator lamps 46 and 47, or as an addition thereto, indication relays R2BK and L4BK govern a non-directional indicator lamp 50, which latter lamp is provided with a circuit including normal polar contact 51 of relay R2BK or normal polar contact 52 of relay L4BK.

In describing the operation of the apparatus I shall assume that the stretch is unoccupied, and it is desired to move an eastbound train from location D to location E. With the stretch unoccupied the track relays of the several track sections are picked up. For reasons to appear hereinafter signal controlling relay R2HSR is normally set at its normal or left-hand position and signal controlling relay L4HSR is normally set at its reverse or right-hand position and the traffic locking circuit is connected to both batteries 12 and 13. Batteries 12 and 13 are made of the same voltage and are poled to oppose each other and thus the traffic locking circuit is normally deenergized. To condition the traffic locking circuit for eastbound traffic the operator at the office station OF operates the proper control lever (not shown) for causing a control code to be sent to coding unit CD of station FD to pick up stepping relay 1F2 and energize signal controlling relay R2HSR at reverse polarity. Since signal controlling relay L4HSR at location E is normally set at its reverse position, the positioning of signal controlling relay R2HSR at location D at its reverse position conditions the traffic locking circuit for energization of directional relay R2FR by current supplied by battery 12, the circuit being formed from one terminal of battery 12 over front contact 52 of an approach locking relay L4LS associated with signals LA4 and LC4 in accordance with standard practice, back contact 54 of directional stick relay L4SR, reverse polar contact 55 of relay L4HSR, front contacts 56, 57, 58 and 59 of track relays 3TR, BTR, ATR and 1TR, respectively, reverse polar contact 60 of relay R2HSR, winding of relay R2FR, reverse polar contact 61 of relay R2HSR, front contacts 62, 63, 64 and 65 of track relays 1TR, ATR, BTR and 3TR, respectively, reverse polar contact 66 of relay L4HSR, back contact 67 of relay L4SR, front contact 68 of relay L4LS, winding of lockout relay L4BLR and to the other terminal of battery 12. Directional relay R2FR and lockout relay L4BLR are now energized and picked up. The picking up of relay R2FR to close front contact 30 controls signal control relay RA2H or RC2H, depending upon the position of switch 1, and in turn causes signal RA2 or RC2 to be operated to a proceed position for permitting an eastbound train to enter this stretch of track. The picking up of lockout relay L4BLR to open back contact 34 locks out the signal controlling relay L4HSR from being energized by a control code that might inadvertently be sent by the operator to station FE while signal RA2 or RC2 occupies a proceed position to permit an eastbound train to move from location D. When the eastbound train enters section 1T, directional stick relay R2SR is picked up as previously explained, and an indication

code is delivered to the office station for operating relay R2BK to its normal position which causes the display of lamp 46 to indicate occupancy of the stretch by an eastbound train, and 5 which opens the coding unit circuit network for code sending relay CS4 to electrically lock the office station coding unit against the sending of a control code to coding unit CE at station FE for control of relay L4HSR and in turn control of signal LA4 or LC4. When the traffic locking circuit is opened due to the shunting of track relay 1TR by the eastbound train, lockout relay L4BLR at location E is retained energized by the traffic locking circuit being completed at location D through back contact 71 of track relay 1TR, front contact 78 of directional stick relay R2SR, a resistor 79 and back contact 80 of track relay 1TR with the result that the lockout relay L4BLR is not released until the train enters section AT 20 to shunt track relay ATR. Thus lockout relay L4BLR is retained energized while the train is passing through section 1T and retains in effect the lockout for signal controlling relay L4HSR until the electric locking of the office station code sending relay CS4 is put into effect. 25 The shunting of track relay 1TR deenergizes its repeater relay 1TP and that relay is released at the end of its slow release period. During the slow release period of repeater relay 1TP the signal controlling relay R2HSR is energized over its second circuit and hence is operated to its normal or left-hand position.

The traffic locking circuit is maintained deenergized as long as the eastbound train occupies 35 the stretch and any one of the track relays is released and hence the electric locking effected at the office station and the display of the directional indicator 46 are continued as long as the eastbound train is moving between the locations D and E. It should be pointed out that directional stick or traffic following relay R2SR when picked up is also used in accordance to standard practice to control signal control relays RA2H and RC2H and in turn to clear either signal RA2 or RC2 as the case may be to permit a second 40 eastbound train to enter the stretch while it is still occupied by the first train. Such control by directional stick relay R2SR is omitted in order to not unduly complicate the drawing since it is 45 not a part of the instant invention and would be according to the well-known arrangement.

The traffic locking circuit is reclosed and then 50 restored to its normal condition when the eastbound train or trains vacate the stretch and the track relays are all picked up. As explained hereinbefore, directional stick relay R2SR is retained energized over its stick circuit while directional relay R2FR is released by the eastbound train in the stretch, and signal controlling relay R2HSR is restored to its normal position when 55 the eastbound train enters section 1T. Hence when the track relays are picked up, one side of the traffic locking is completed over normal polar contact 71 of relay R2HSR and front contact 89 of relay R2SR and the other side of the circuit is completed over normal polar contact 74 of relay R2HSR and front contact 90 of relay R2SR, and relay R2FR is reenergized and picked up. Relay R2FR on picking up opens the stick circuit of relay R2SR and relay R2SR is released 60 opening front contacts 89 and 90 to reopen the traffic locking circuit and release relay R2FR with the result the traffic locking circuit is restored to its normal condition.

75 Directional stick relay R2SR upon being re-

leased to close its back contact 38 causes the sending of an indication code which operates indication relay R2BK to its reverse position with the result that the electric locking against code sending relay CS4 is released and the directional indicator 46 is extinguished. Also indicator 50 if provided would be extinguished when relay R2BK is restored to its reverse position.

Assuming that the stretch is unoccupied and it is desired to move a westbound train from location E to location D, the operator sends a control code to coding unit CE at station FE as required to pick up stepping relay 3F2 and energize signal controlling relay L4HSR at normal polarity. Since relay R2HSR occupies its normal position, the energization of relay L4HSR at normal polarity conditions the traffic locking circuit for energization of the directional relay L4FR by current supplied by battery 13. The traffic locking circuit can now be traced from one terminal of battery 13 over front contact 69 of an approach locking relay R2LS associated with signals RA2 and RC2 in accordance with standard practice, back contact 70 of relay R2SR, normal polar contact 71 of relay R2HSR, front contacts 59, 58, 57 and 56 of the several track relays, normal polar contact 72 of relay L4HSR, winding of directional relay L4FR, normal polar contact 73 of relay L4HSR, front contacts 65, 64, 63 and 62 of the several track relays, normal polar contact 74 of relay R2HSR, back contact 75 of relay R2SR, front contact 76 of relay R2LS, winding of lockout relay R2BLR and to the other terminal of battery 13. Directional relay L4FR and lockout relay R2BLR are now energized and picked up. The picking up of directional relay L4FR to close front contact 31 selects either relay LA4H or LC4H and causes either signal LA4 or LC4 to be operated to a proceed position, depending upon the position of switch 3. The picking up of lockout relay R2BLR to open back contact 37 locks out the control of relay R2HSR by any control code sent from the office station to the field station FD while signal LA4 or LC4 occupies a proceed position. When a westbound train enters section 3T to shunt track relay 3TR, the traffic locking circuit is disconnected from directional relay L4FR and that relay is released, causing the directional stick relay L4SR to be picked up and then retained energized over its stick circuit. The picking up of directional stick relay L4SR to close front contact 44 causes the sending of an indication code from the field station FE which operates indication relay L4BK to its normal position with the result that electric locking is effected for the code sending relay CS2 and the directional indicator lamp 47 is illuminated to indicate occupancy of the stretch by the westbound train. While the westbound train is in section 3T, the traffic locking circuit is completed at back contact 81 of relay 3TR, front contact 82 of relay L4SR, resistor 83 and back contact 84 of relay 3TR with the result that the lockout relay R2BLR is retained picked up to hold the lockout against relay R2HSR in effect until the electric locking is made effective at the office station. The shunting of track relay 3TR by the westbound train deenergizes the respective repeater relay 3TP and that relay is released at the end of its slow release period. During the interval repeater relay 3TP is picked up and track relay 3TR is released, the second circuit for relay L4HSR is closed and relay L4HSR is operated back to its reverse position.

Thus, when the westbound train vacates the stretch, one side of the traffic locking circuit is completed at location E over reverse polar contact 55 of relay L4HSR, and front contact 91 of relay L4SR and the other side of the circuit is formed over reverse polar contact 66 of relay L4HSR and front contact 92 of relay L4SR, with the result that directional relay L4FR is reenergized and picked up. When directional relay L4FR is picked up, directional stick relay L4SR is released to reopen the traffic locking circuit and deenergize relay L4FR restoring the traffic locking circuit to its normal condition. Release of relay L4SR causes an indication code to be sent for operating the indication relay L4BK to its reverse position where the electric locking against code sending relay CS2 is released and the indicator lamp 47 is extinguished.

It is to be pointed out that the alternative indicator 50, if used, is illuminated when the westbound train occupies the stretch and is extinguished when the train vacates the stretch and relay L4BK is restored to its reverse position. It is also to be observed that directional stick relay L4SR would be used to control relays LA4H and LC4H to permit following westbound movements in accordance to the usual practice.

While in the present embodiment of the invention the traffic locking circuit is shown as including lockout relays R2BLR and L4BLR such relays may not be required when the invention is used with a traffic locking circuit of the so-called interlocking-code system of control in which there is the electrical equivalent of mechanical locking between opposing signal lever relays.

It is to be seen therefore that I have provided novel means by which the traffic on a stretch of railway controls electric locking and directional indication for a remote control system through the medium of relays already provided in such system and additional circuits and relays to repeat the conditions of the different track circuits of the stretch of railway involved are avoided.

Although I have herein shown and described but one form of railway traffic controlling apparatus embodying my invention, it is understood that various changes and modifications may be made therein within the scope of the appended claims without departing from the spirit and scope of my invention.

Having thus described my invention, what I claim is:

53. 1. In railway traffic controlling apparatus for a stretch of railway track divided into track sections each having a track relay, the combination comprising, a line circuit extending from one end to the other of said stretch and including a front contact of each of said track relays, a directional relay and a traffic following relay at each end of the stretch, a manually controlled relay at each end of the stretch having contacts which in one position connect the associated directional relay and in another position connect a source of current to the adjacent end of said line circuit, means for energizing each traffic following relay if the associated directional relay is released due to a train entering the stretch at the corresponding end, means for holding each traffic following relay energized until the associated directional relay is again energized, remote control means at a control office for governing said manually controlled relays, two indication relays at said office one for each end

of said stretch, means at each end of the stretch including contacts of the associated traffic following relay to control the associated indication relay to a first or a second position according as a back contact or a front contact of the associated traffic following relay is closed, a block indication lamp at said office, and means controlled by each said indication relay in its first position for rendering said remote control means effective to control the manually controlled relay associated with the opposite end of the stretch and in its second position to light said block indication lamp.

2. In railway traffic controlling apparatus for a stretch of railway track divided into track sections each having a track relay, the combination comprising, a line circuit extending from one end to the other of said stretch and including a front contact of each of said track relays, a directional relay and a traffic following relay at each end of the stretch, a manually controlled relay at each end of the stretch having contacts which in one position connect the associated directional relay and in another position connects a source of current to the adjacent end of said line circuit, means for energizing each traffic following relay if the associated directional relay is released due to a train entering the stretch at the corresponding end, means for holding each traffic following relay energized until the associated directional relay is again energized, remote control means at a control office for governing said manually controlled relays, a directional indication lamp for each direction of traffic through the stretch at said control office, and means remotely controlled by each said traffic following relay when energized for lighting the corresponding one of said directional indication lamps.

3. In railway traffic controlling apparatus for a stretch of railway track divided into track sections each having a track relay, the combination comprising, a line circuit extending from one end to the other of said stretch and including a front contact of each of said track relays, a directional

relay and a traffic following relay at each end of the stretch, a manually controlled relay at each end of the stretch having contacts which in one position connect the associated directional relay and in another position connect a source of current to the adjacent end of said line circuit, means for energizing each traffic following relay if the associated directional relay is released due to a train entering the stretch at the corresponding end, means for holding each traffic following relay energized until the associated directional relay is again energized, remote control means at a control office for governing said manually controlled relays, a directional indication lamp for each direction of traffic through the stretch and a block indication lamp at said office, and means remotely controlled by each traffic following relay when energized for lighting the corresponding one of said directional indication lamps and for also lighting said block indication lamp.

4. In railway traffic controlling apparatus for a stretch of railway track divided into track sections each having a track relay, the combination comprising, a line circuit extending from one end to the other of said stretch and including a front contact of each of said track relays, a directional relay and a traffic following relay at each end of the stretch, a manually controlled relay at each end of the stretch having contacts which in one position connect the associated directional relay and in another position connect a source of current to the adjacent end of said line circuit, means for energizing each traffic following relay if the associated directional relay is released due to a train entering the stretch at the corresponding end, means for holding each traffic following relay energized until the associated directional relay is again energized, a block indication lamp at a control office from which said manually controlled relays are governed, and means at said office remotely controlled by said traffic following relays for lighting said block indication lamp when either one of said traffic following relays is energized.

CHARLES W. BELL.
